D19520

FIG. 1.

FIG. 2.

UNITED STATES PATENT OFFICE.

CHARLES A. DAVIS, OF WASHINGTON, DISTRICT OF COLUMBIA.

DESIGN FOR A GUNSTOCK.

SPECIFICATION forming part of Design No. 19,520, dated December 24, 1889.

Application filed November 25, 1889. Serial No. 331,556. Term of patent 14 years.

To all whom it may concern:

Be it known that I, CHARLES A. DAVIS, a citizen of the United States, residing at Washington, in the District of Columbia, have invented a certain new and original Design for the Stocks of Guns or Fire-Arms, of which the following is a specification.

My invention consists in a novel design for the stock of a gun, by which term I mean to include all that class of fire-arms which have a stock designed to rest against the shoulder when the arm is fired, but to exclude revolvers, pistols, and like weapons which are simply held in one hand.

My design is illustrated in the annexed photographs, Figures 1 and 2 of which show opposite sides or faces thereof.

As shown, the general outline of the stock A is the same as usual; but the rounded neck a, variously designated in the trade as the "handle," "hand," or "small," is formed with a series of alternating ridges and depressions conforming more or less closely to the fingers, thumb, and palm of the hand, as clearly

shown in the photographs, and designed to fit the hand as it grasps the stock in using the arm.

The distinguishing features of the design are the series of ridges and depressions and the irregular surface illustrated, which may be best described as presenting the appearance of a plastic body which has been grasped by a human hand and firmly pressed or squeezed, leaving the imprint of the hand at that point and in that position which the hand would naturally occupy in aiming or firing the gun.

Having thus set forth my invention, I claim—

The design for stocks of guns or fire-arms herein described and shown.

In witness whereof I hereunto set my hand in the presence of two witnesses.

CHARLES A. DAVIS.

Witnesses:

O. M. BALL,
CHARLES G. RINGWALT.
